UNITED STATES PATENT OFFICE.

THOMAS J. BUTLER, OF COLUMBUS, OHIO.

HEEL-BONE SUPPORT.

Application filed December 22, 1924. Serial No. 757,494.

The great majority of fallen arches are caused by the wearing of shoes which elevate the heel beyond the point which nature intended it to occupy. When the foot rests in its natural position, there is practically no tendency for the heel bone or oscalcis to move rearwardly at its lower or rear end and to lower at its upper or front end under the weight of the body, and what tendency exists is effectively overcome by the ligaments tying the heel portion of the arch to the toe portion thereof, with the result that falling of the arch is prevented. When shoes are worn however, which elevate the heel but not the toe of the foot, the heel bone is forced to occupy a position in which it projects rearwardly more nearly on a horizontal line, and in this position, the weight of the body acting downwardly on the front end of the heel bone is not as effectively supported and exerts a tremendous force tending to swing this bone in a manner to cause its upper end to lower and its lower end to move rearwardly. Combining with this force, is the tendency of the front portion of the arch to slide forwardly, down the inclined portion of the shoe sole. These combined forces are so great that the ligaments connecting the heel and toe portions of the arch cannot withstand them, with the result that the ligaments stretch, allowing the ends of the arch to move away from each other and consequently permitting the crown of the arch to fall.

The average arch support exerts upward pressure on the middle of the arch and the above-mentioned ligaments and in so doing, necessarily exerts a stretching action on such ligaments, tending to aggravate the trouble and possessing no corrective characteristics whatever.

It is the principal object of my invention to provide a new form of support which will not only effectively support a foot with a fallen arch, but will do so without placing any strain on the arch holding ligaments tending to further stretch them. Thus, these ligaments, relieved of strain, may contract to their proper lengths, so that the trouble is corrected.

With the foregoing in view, the invention resides in the novel subject matter hereinafter described and claimed, the description being supplemented by the accompanying drawings.

Figure 1 is a perspective view of a specially prepared last upon which the improved support may be formed.

Figure 2 is a perspective view illustrating a thick piece of leather or some equivalent material secured upon the last to have its upper side shaped by the latter.

Figure 3 is a view similar to Fig. 2 but illustrating the support in a finished condition upon the last.

Figure 4 is a sectional view of a shoe embodying the support, illustrating by the arrow A, the point at which the support exerts pressure on the heel bone or oscalcis.

Figure 5 is a perspective view of the support separate from the shoe.

Figure 6 is a longitudinal sectional view as indicated by line 6-6 of Fig. 5.

Figure 7 is a transverse sectional view on line 7-7 of Fig. 5.

Figure 8 is a transverse section through the heel portions of a pair of the supports, cut substantially on the plane of the line 8-8 of Fig. 5, looking in the direction of the arrows.

Figure 9 is a diagram showing first, the normal position of the foot, and second, the position which it assumes when a rather high heeled shoe is worn, these views being included in order that the defect to be corrected, may be more readily explained.

In the drawings above briefly described, both the finished article and one manner of manufacture, are shown, and the article will be first described. The numeral 1 designates a horizontally elongated body which is preferably formed of leather, although it could well be constructed from any other adequate material. This body is adapted for disposition in a shoe, as shown in Fig. 4, and it is of a length to cover the shoe heel and at least a portion of the shank of the sole, said body being transversely concave on its upper surface from its rear end substantially to its front end. The upper side of the body 1 is also longitudinally concave from its rear end to a point 2, said point being near but behind the front extremity of the heel portion of the body. The concavity behind the point 2, forms a pocket 3 to receive the rear and intermediate portions of the user's heel, but immediately in front of said point 2, the upper surface of the body 1 is longitudinally convex, providing a crest 4 to support the front portion of the heel and exert an upward pressure on the front end of the heel.

bone or oscalcis, as indicated by the arrow A in Fig. 4. The front portion of the body 1 tapers forwardly from the crest 4 to prevent exertion of pressure under the middle 5 of the longitudinal arch of the foot, distinguishing my invention from the ordinary arch support which is intended to exert pressure under the middle of the arch, instead of under the front end of the heel bone. 10 The lower surface of the heel portion of the body 1, is preferably flat as indicated at 6, and from this flattened portion, the lower side of the body is cut away to laterally taper the intermediate and front portions of 15 said body to feather edges, as indicated at 7. Furthermore, the body is cut away on its lower side to produce the taper 5 which also extends to a feather edge. The upper side of the heel portion of the body 1, forming 20 the pocket 3, is preferably shaped as indicated in Fig. 8, so as to more readily accommodate the shape of the heel, in which the heel bone declines outwardly to some extent, as well known. 25 In manufacturing the support, I may make use of a specially prepared last L (Figs. 1, 2 and 33). This last is provided with a heel surface H which is convex both longitudinally and transversely, and the 30 shank surface S is transversely convex and preferably higher at one side than at the other, so that the support to be formed thereon, will more readily engage the wearer's foot. I apply a thick piece of leather or 35 the like to the surfaces H and S, this piece of material being preferably soaked with water before its application to the last. Then, the edges of the piece of material are tacked down to the last and in this condition, it is allowed to remain until substantially dry. 40 Thus, the last imparts the desired shape to the upper side of the piece of material, to form the upper side of the support, hereinbefore described. At the same time, the lower side of this piece of material is given a convex formation as indicated at C in Fig. 2. The convexity is cut away 45 at the heel portion to provide the flat surface 6, and from this surface, the piece of material is skived to forwardly taper it and to laterally taper it in opposite directions. The lateral tapers impart to the shank, substantially the crescent shape shown more particularly in Fig. 7, and the lower side of 50 this crescent-shaped shank portion is adapted to rest snugly upon a similarly shaped shank portion 8 of an inner sole 9 which is suitably secured in the shoe. Preferably, a metal reinforcement 10 is secured to the upper surface of this inner sole before the latter is secured in the shoe, and this reinforcement underlies the crest 4 of the support, to prevent appreciable sagging thereof, although permitting slight downward yielding. 65 Obviously, the body 1 may be cemented

in place or otherwise secured, and if desired a sock lining may extend over the upper surface of the support and the portion of the inner sole 9 in advance thereof.

By reference to Fig. 9, the practicability 70 of the invention will be more readily understood. In this view, 20 designates the leg bone, 21 has reference to the astragalus, 22 designates the oscalcis or heel bone which forms the rear portion of the longitudinal 75 arch of the foot, and 23 refers to the bones constituting the front portion of the arch. These same numerals are applied to Fig. 4.

The left portion of Fig. 9 represents the human foot in the position which nature intended it to occupy, with the front and rear portions of the arch horizontally aligned at their lower ends. When the foot is in this position, the weight of the body acting downwardly on the heel bone 22, has practically no tendency to move the front end of this bone downwardly and its rear or lower end rearwardly, and what tendency exists, is counteracted by the muscles which connect the front and rear portions of the arch. As soon as a shoe is worn with a heel which elevates the rear end of the foot arch to a point above the front end thereof, as indicated at the right-hand portion of Fig. 9, the heel bone 22 projects rearwardly 80 more nearly on a horizontal line. When in this position, the weight of the body acting downwardly on the front end of this heel bone, is not effectively supported by the latter and consequently it exerts a force which tends to swing this bone in a manner to cause its upper end to lower and its lower end to move rearwardly. At the same time, the front portion 23 of the arch has a tendency to slide forwardly down the incline 85 of the shoe sole. Thus, the heel portion of the arch pulls rearwardly on the ligaments which connect it with the front of the arch, and at the same time, said front of the arch pulls forwardly on these ligaments, and with the foot improperly supported, in this unnatural position, the stretching force exerted on the muscles is so great that they cannot withstand it, with the result that they do stretch, permitting the front and rear ends of the arch to move away from each other and consequently permitting the crown of the arch to fall, causing the very serious 90 well-known troubles. By the use of my invention, I support the front end of the heel bone 22, as indicated by the arrow 24 in Fig. 9. Thus, the front end of this bone cannot be depressed under the weight of the body and consequently its rear end cannot be forced rearwardly and exert a stretching action on the foot muscles, the result being that the arch is held in its proper shape and the muscles previously stretched are given a chance to naturally contract, so that the foot 95 trouble is effectively corrected. This correc- 100

tion would not be permitted, if upward pressure were exerted under the middle of the arch, as such upward pressure, I have found, draws the foot ligaments tight between the heel and toe portions of the arch and subjects them to a further stretching action, instead of having any corrective characteristics.

From the foregoing, taken in connection with the accompanying drawings, it will be seen that I have produced a distinct advance in the art of correcting foot troubles. As excellent results may be obtained from the method and construction herein described, such method and construction may well be followed. However, within the scope of the invention as claimed, modifications may of course be made.

I claim:

1. An oscalcis support for disposition in a shoe, said support comprising an elongated body of a length to cover the shoe heel and the shank portion of the sole, said body

being transversely concave on its upper surface from its rear end substantially to its front end, being longitudinally concave from its rear end to a point near but behind the front extremity of its heel portion, and being longitudinally convex in front of said concave portion, providing a crest for disposition under the front end of the oscalcis, said body being forwardly tapered from said crest to prevent exertion of pressure under the middle of the longitudinal arch of the foot, the transverse cavity of said body extending forwardly beyond said crest.

2. A structure as specified in claim 1; the lower side of said body being flat at its heel portion and being transversely convex from said flat portion to the front end of the body.

In testimony whereof I have hereunto affixed my signature.

THOMAS J. BUTLER.
